UNITED STATES PATENT OFFICE.

WARREN A. PATTERSON, OF DALLAS, TEXAS.

COTTON-BOIL SEPARATOR.

1,130,102.

Specification of Letters Patent. Patented Mar. 2, 1915.

Application filed January 16, 1914. Serial No. 812,372.

To all whom it may concern:

Be it known that I, WARREN A. PATTERSON, citizen of the United States, residing at Dallas, Dallas county, Texas, have invented certain new and useful Improvements in Cotton-Boll Separators, of which the following is a specification.

This invention relates to new and useful cotton boll threshing machines and is particularly adapted for breaking up dry cotton bolls, cleaning and separating the fiber from the boll and stem.

Primarily the object of the invention is to provide means for crushing, agitating and opening the dry cotton bolls and removing the fiber or seed cotton from same without breaking the fiber and lowering the grade of the staple.

An object of the invention is to have an agitating chamber provided with a number of slots through which the cotton fiber will be discharged, either by suction or air pressure.

Another object of the invention is to provide a vacuum or discharge chamber positioned adjacent to the agitating chamber and adapted to receive and convey the cleaned lint cotton away from the machine and also to provide a similar discharge or vacuum box to convey off the bolls and other waste material.

With these and other objects in view, the invention has relation to certain novel features of construction and operation, an example of which is described in the following specification and illustrated in the accompanying drawings, wherein:

Figure 1 is a sectional view of the cotton separating machine in side elevation. Fig. 2 is a sectional view of the machine the section being taken upon the line $x-x$ of Fig. 1. Fig. 3 is a sectional view taken upon the line $m-m$ of Fig. 1. Fig. 4 is a sectional view in plan, the section being taken upon the line $y-y$ of Fig. 1. Fig. 5 is a partial view of one of the revolving agitators. Fig. 6 is a view taken upon the line $a-a$ of Fig. 4.

Referring now more in particular to the drawings, wherein similar reference characters designate the same parts throughout the several views, the letter A designates the agitating chamber and the numerals 1 and 2 the top and bottom walls of said chamber. The side walls are respectively

designated by the numerals 3 and 4. The ends 6 complete the walls of the chamber. All walls are joined substantially air tight. The structure just referred to is supported by a plurality of transverse bars, said bars being in turn flushly joined at right angles with two longitudinally parallel beams 7 which are in turn supported by the legs 8.

The bottom or floor 2 of the agitating chamber is preferably of rolled sheet steel or similar material, and as shown in Fig. 4, is formed of a number of strips or sections. These floor sections are shown spaced apart providing a plurality of longitudinal slots or openings 9. Means are provided for varying the width of these slots. This is done by shifting the sections farther apart or closer together. To accomplish this end one section 2^a is, in this case, permanently secured by screws 10 to the bars 6. The other sections 2 of the floor are provided with slots 11 through which are inserted the screws 10, said screws being adapted to rigidly and firmly hold the sections in place after said sections have been laterally adjusted and the widths of the slots have been proportioned.

The slots 9 in the floor of the agitating chamber will generally, in the use of the machine, be of the same width throughout. But the provisions furnished for shifting the movable sections make it possible to vary the width of the slot throughout its entire length, or to make the said slot wider at one end than the other. A solid floor 12 of substantially the same material as the floor 2 adjoins the said floor sections 2 and is adapted to perform functions hereinafter set forth.

A number of horizontally parallel agitator shafts 14 are longitudinally mounted in the agitating chamber and journaled in bearings 15. A pulley 16 is fixed to one of the shafts and is adapted to receive its power from any suitable form of motive power. The shafts will preferably equal in number the number of slots carried in the floor of the chamber.

A plurality of arms 16 are carried by the shafts 14, and are arranged in the same plane upon said shaft. The plurality of shafts 14 have their arms 16 so arranged, as illustrated, that they will revolve in proximity with each other without interfering. The extremities of the arms 16 rigidly carry

a reach beam 17 which in turn carries a flexible wiper 18 of leather or other suitable material upon its edge. The wiper is secured to the reach beam with rivets or brads as designated by the numeral 19 and has its edge extend beyond the outer edge of the beam 17. As will later be seen the wipers are adapted to pass across the slots and flex or yield to the cotton bolls or fiber which may be in the slots.

10 A hopper 20 is provided at one end of the machine to receive the cotton. The cotton will be pulled in this hopper by the suction of an element of the machine later mentioned.

15 A discharge or vacuum chamber B is carried beneath the chamber A and has its side walls 21 contiguous with the inner edges of the beams 7. The floor or bottom of the chamber B is designated by the numeral 22. The ends 23 of said chamber B close and form a substantial air tight chamber.

20 A train of spur gears 14^a are fixed upon the shafts 14 and are adapted to drive said gears.

25 It is now seen how the slots 9 form the only passage way from the agitating chamber A to the discharge chamber B. An air chute 24 communicates with one extremity of the chamber B. This air chute, in actual practice and operation of the machine, is adapted to connect with a centrifugal exhauster or vacuum pump, (not shown). This it will be seen sets up a vacuum throughout the machine, a further description of same will be later hereinafter given.

30 An outlet 25 is provided in the wall 4 of the chamber A. This outlet as seen is in the end of the machine opposite the hopper 2 and opens directly into a vacuum box or discharge chute 26. The side walls 27 of the vacuum box lie contiguous with the wall 4 of the chamber A and forms a substantial air tight compartment accessory to said chamber A. Said vacuum box forms an exit and means of disposal for the waste product such as bolls, stalks and dirt. Journaled in bearings 28 in the lower extremities of the walls 27 of the vacuum box is a horizontal shaft or feeder 29. Said shaft carries a pulley 29^a and four radiating vanes 30 disposed at right angles about the shaft. These vanes are equal in length to the distance between the side walls 27. Flexible wipers 31, similar to the wipers 18, are carried upon the outer edges of the vanes 30. A pair of arcuate plates 32 are disposed in the lower portions of the chute 26 and the upper portion of said plates have such a contour and shape as will form a substantially funnel shaped feed to the feeder 29; while the lower portions are arcuate in form and encompass the feeder 29 with a radius equal to that of the radius of one of the vanes 30.

35 In the operation of the machine motive

power will be applied to the pulley 16 which will impart motion to the agitators 14, in such a direction that the agitator adjacent to the opening 25 in the side wall 4 will turn in a counter clockwise direction. This direction adapts the agitator to sweep the refuse or bolls from the solid floor 12 through the opening 25 into the vacuum box. Motive power will also be applied to the pulley 29 which will slowly revolve the feeder 29. The air chute 24 should now communicate with a vacuum fan (not shown) and a vacuum set up through the chute and correlated chambers A and B. It is here to be understood that the slots 9 will be adjusted in width just sufficient to prevent the cotton bolls, that is the dry bolls and other refuse, from falling through into the chamber B. The slots are adapted to allow the cotton fiber or seed cotton only to pass through and prevent the broken bolls, stems and other waste product from passing into the chamber B. The unharvested and dry bolled cotton will now be fed in through the hopper 2. The revolving agitators and suction through the slots 9 will distribute the bolls over the floor of the chamber A. The draft through the slots will draw the dry bolls over and against the edges forming the slots, but not through said slots. The revolving wipers 18 of the agitators will pass in close contact to the slot and crush and open the dry bolls. The exposed fiber is immediately drawn through the slot 9 and into the discharge chamber and passes out through the air chute and exhausting fan. The bolls and other waste products are gradually worked toward the opening 25 and are thrown into the vacuum box 26. The purpose of the vacuum box is to dispose of the refuse without allowing any air into the machine which would lower the vacuum in the machine. The feeder 29 slowly revolves and as seen will always have two vanes brushing in contact with the members 32. This will discharge the bolls and refuse and allow only a minimum of air to enter.

40 In some cases air pressure might be used through the machine rather than suction. In this case a draft of air would be passed in through the hopper 21 and along with the cotton to be harvested or separated. This method would tend to press the cotton fiber through the slots rather than pull it through.

45 This invention is presented as including all such modifications and changes as may properly come within the scope of the following claims.

50 What I claim is:

55 1. A cotton separating machine consisting of a chamber having a hopper at one end and an outlet near the other end, the floor of said chamber having adjustable slots for the passage of the seed cotton, means within said chamber to break the bolls and dis-

charge the hulls through the outlet, and suction means to draw the seed cotton through the slots.

2. In a cotton separating machine consisting of a chamber having a receiving hopper and an outlet, the floor of said chamber having a plurality of adjustable slots for the passage of the seed cotton, a plurality of horizontal shafts in the chamber, flexible 10 wipers correlated with the shafts and adapted to wipe the slots in the floor and suction means to draw the seed cotton through the slots.

3. In a cotton separating machine consisting of a chamber having a receiving hopper and an outlet, the floor of said chamber having a plurality of adjustable slots for the passage of the seed cotton, a plurality of horizontal shafts in the chamber, flexible 15 wipers correlated with the shafts and adapted to wipe the slots in the floor and pressure 20 means to draw the seed cotton through the slots.

means for forcing the seed cotton through the slots.

4. In a cotton boll separating machine, an 25 agitating chamber, an inlet hopper at one end and an outlet near the other, the floor of said chamber having adjustable slots for the passage of seed cotton, shafts arranged longitudinally within the agitating chamber and arranged above the slots, arms carried by the said shafts, reach beams carried by the extremities of the arms, flexible 30 wipers carried by the beams and suction means provided for drawing the seed cotton through the slots. 35

In testimony whereof I affix my signature in the presence of two witnesses.

WARREN A. PATTERSON.
